UNITED STATES PATENT OFFICE

FREDERICK LAMATSCH, OF GRANTWOOD, NEW JERSEY, ASSIGNOR TO R. HOE & CO., INC.,
OF NEW YORK, N. Y., A CORPORATION OF NEW YORK

FOLDER FOR WEB PRINTING MACHINES

Application filed November 30, 1929. Serial No. 410,715.

This invention relates to folders for web printing machines and especially machines of the type used for printing newspapers and similar products.

5 Machines of this class that are in use in press rooms of the larger newspapers, are equipped with double folders so arranged that both sides of the folder may be used simultaneously, or either side may be used 10 separately.

Folders are usually arranged with their deliveries placed one on each side of the machine, but in some instances, it is necessary to place one side of the press quite close to 15 a wall, and in such cases, there is insufficient working space for removing the printed 20 papers from the rear delivery.

Arrangements have been used in which both deliveries were located at one side of the 25 machine as disclosed in Schmidt Patent No. 1,494,378, which shows an arrangement of conveyors which deliver the product of two folders at one side of the machine, and the two products are carried closely adjacent to 30 each other. In many cases it is preferable to keep the deliveries separated so that should anything happen to interfere with the operation of either delivery and cause a choke, the 35 operation of the other one will not be affected.

Other arrangements for bringing both deliveries to the front side of the machine have been used in which the delivery coming from the rear of the machine was arranged on a 40 descending incline so that it might pass under the front delivery and still allow sufficient space between them to give the requisite accessibility. Some difficulty was experienced with this arrangement however, for it was found that the papers would slip forward 45 while they were on the inclined section of the delivery belts.

With the arrangement described herein, the cutting and collecting cylinders, and the delivery fan wheels are arranged in staggered 45 relation, with the rear group at a lower level than the front group, and the delivery from the rear group is carried on a substantially level plane, directly to the front of the machine. The use of a downwardly inclined 50 delivery is thus avoided, there is no liability

of a choke on either of the deliveries interfering with the operation of the other delivery, and there is ample space for access to the papers while they are on the delivery belts.

The object of the invention is to provide an arrangement for a double folder wherein both deliveries have their belts running on a substantially horizontal plane to the front side of the machine and separated from each other 60 so that the printed products on the delivery belts are accessible. 55

It is also an object of the invention to provide a double folder with front deliveries, that is of generally improved construction, 65 whereby the device is simple, in construction, as well as convenient, practical, serviceable and efficient in its use. 60

With the foregoing and other objects in view, which will appear as the description 70 proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention. 75

The preferred embodiment of the invention is illustrated in the accompanying drawing which shows an outline view of a double folder, as seen when looking at the folder end of the printing machine. A machine equipped with this folder is adapted for mounting with one side close to a wall or other 80 obstruction, as the products from both cutting mechanisms are brought to one side of the press, which is herein referred to, as the front side. 85

The base frame of the machine is indicated 90 by the numeral 11, the front side frame by 12, the rear side frame by 13 and a cross frame by the numeral 14. Formers of the usual type are shown partly broken away at 15 and 15'. The cutting cylinders are indicated at 95 16 and 16' and cooperate respectively with folding cylinders 17 and 17' which, in accordance with the usual practise may fold either a collected or an uncollected product which is passed between the folding off rollers 18 100

- and 19 or 18' and 19'. The folded papers then pass to fan wheels 21 or 21' and are delivered to the delivery belts 22 or 22'. Means for driving the folder may consist of a shaft 5 indicated at 23 which is connected by mitre gears 24 and 25 to the vertical shaft 26 that is supported in suitable bearings in brackets 27 secured to the frame 13. The bevel gear 28 meshes with the bevel gear 29 on the shaft 10 31 that is rotatably supported in brackets 32, 33 and 34 secured respectively to frames 13, 14 and 12, and bevel gears 35 and 35' mesh with mating gears connected respectively with the cylinders 17 and 17'. 15 It will be understood that in accordance with the usual practise, suitable gearing is provided to connect the folding cylinders 17 and 17' with their cutting cylinders 16 and 16' so they are driven in proper timed relation. 20 Similarly, in accordance with the usual practise which is well known to those versed in the art, the fan wheels 21 and 21' are driven by suitable gearing from the cylinders 16 and 16', and the delivery belts 22 and 22' are driven through bevel gears on the shafts 36 and 36' respectively, which carry worm wheels meshing with worms on the shafts of the wheels 21 and 21'. 25 The delivery belts 22 pass around pulleys 30 on the shaft 37 and other pulleys 38 supported by the arms 39, that in turn are supported on a rod 41, secured to the frame 14. Other delivery belts 42, are arranged to convey the papers to a remote point. Likewise, delivery belts 22' pass around pulleys on the shaft 37' over an idler pulley 43, and around pulleys 44. Delivery belts 45, pass around pulleys 44 and 46, and delivery belts 42' extend from pulleys 46, to a remote point. 35 A printed web or group of webs is led over the former 15, where it receives its first fold, and it is then passed to the cutting cylinders where it is cut into sheets that are folded by the cylinder 17 and passed between the folding off rollers 18 and 19, where they receive the second fold. The products then pass on to the fan wheel 21, which deposits them on the delivery belts 22, from which they are forwarded to and by the belts 42. 40 It will be understood that similarly, webs led over the former 15' are deposited on the belts 22' and forwarded by the belts 45 and 42'. It will also be understood that all or parts of the webs passing over either of the 45 formers may be deflected to the opposite cutting mechanism, as shown by the dotted lines 47 and 48. Thus, all the webs coming from the former 15 may follow the course of the dotted line 48, and become associated with webs coming from the former 15', in which case, the associated product would be deposited on the delivery belts 22'. 50 It will be seen that the arrangement of the delivery belts is such that the folded papers 55 coming from the press are conveyed either

on a substantially horizontal plane or in an upward direction after they are placed on the delivery belts by the fan wheels. It has been found that under such conditions, the papers are forwarded in an orderly manner, but if the delivery belts are so arranged that at any place their path is inclined downwardly more than to a slight extent, there is a tendency for the papers to slide forward and become disarranged. 70

The arrangement disclosed herein whereby the cutting mechanism of the rear folder is placed on a lower level than the cutting mechanism of the front folder, and by which the delivery belts of the rear delivery are carried on a substantially horizontal plane below the front delivery, permits ample space for the operator to obtain access to all of the mechanism; and the arrangement whereby the shaft 31 is supported in a diagonal position with respect to the frame and which permits both folding cylinders to be geared to the same shaft, avoids lost motion and the more expensive construction incident to a less direct driving connection. 80

The plates are usually placed on the printing cylinders in such manner, that the printed papers will be delivered with their headings facing upward, as this method facilitates handling. With presses having their deliveries at opposite sides, when the webs passing over both formers are associated, and carried to one of the deliveries, they will be delivered with the headings facing upward, but if the webs are carried to the other delivery, they will be delivered with the headings facing downward. By arranging the folder so that both deliveries are carried to the same side of the machine, the papers are delivered in the same manner when using either folder. It will thus be understood that with the arrangement of deliveries herein disclosed, should any trouble develop with one of the deliveries when making an associated run, the lead of the webs can quickly be 90 changed to the other delivery and still deliver the papers facing the same way. 100

What I claim is:

1. In a double folder for a web printing machine, a first cutting and folding mechanism with a delivery, and a second cutting and folding mechanism located beside the first mentioned mechanism and on a lower level, with a second delivery extending horizontally beneath the first delivery and separated therefrom. 110

2. In a double folder for a web printing machine, two folding and cutting mechanisms arranged in side by side relation, with the first mechanism on a higher level than the second mechanism, and two delivery mechanisms both having their discharge ends at the same side of the machine, the first delivery being above the second delivery and spaced therefrom. 120

3. In a double folder for a web printing machine, a first cutting and folding mechanism with a first delivery arranged to discharge a product at one side of the machine, 5 and a second cutting and folding mechanism located beside the first mechanism and on a lower level, with a second delivery arranged to discharge a product at the same side of the machine as the first delivery; said second 10 delivery having belts running in a substantially horizontal plane from a point below the second cutting and folding mechanism, to the side of the machine.

4. In a folder for a web printing machine, 15 two formers in alignment transversely of the machine, two cutting mechanisms in operable association with the formers, and a delivery for each cutting mechanism, said deliveries both being arranged to discharge 20 their products at the same side of the machine, and the cutting mechanism that is remote from the side of the machine to which the products are delivered being placed on a lower level than the other cutting mechanism, 25 whereby its delivery may be spaced away from the other delivery and pass horizontally below it.

5. In a double folder for a web printing machine, a front cutting and folding mechanism with a front delivery adapted to discharge a product at the front side of the machine, and a rear cutting and folding mechanism with a rear delivery adapted to discharge a product at the front side of the 35 machine; said rear cutting and folding mechanism being on a lower level than the front cutting and folding mechanism, and the rear delivery passing horizontally beneath the front delivery and spaced therefrom.

40 6. In a folder for a web printing machine, a front cutting and folding mechanism with a front delivery adapted to discharge a product at the front side of the machine, a rear cutting and folding mechanism with a rear delivery adapted to discharge a product at the front side of the machine, and a common 45 means for driving both cutting and folding mechanisms, including a diagonally supported shaft.

50 7. In a folder for a web printing machine, a folder frame, a front cutting and folding mechanism at one side of the frame, a rear cutting and folding mechanism at the other side of the frame and on a lower level, and 55 a diagonally supported shaft for driving both cutting and folding mechanisms.

In testimony whereof, I affix my signature.
FREDERICK LAMATSCH.
